UNITED STATES PATENT OFFICE.

ALBERT H. CARRIER, OF ASHEVILLE, NORTH CAROLINA, ASSIGNOR OF ONE-HALF TO
EDWIN W. GROVE, OF ST. LOUIS, MISSOURI.

WOOD-CUTTING MACHINE.

Application filed April 11, 1922. Serial No. 551,615.

To all whom it may concern:

Be it known that I, ALBERT H. CARRIER, a citizen of the United States, residing at Asheville, in the county of Buncombe and State of North Carolina, have invented new and useful Improvements in Wood-Cutting Machines, of which the following is a specification.

This invention relates to wood cutting or veneer slicing machines, and the primary object of the invention is to provide a machine that will effectively cut slices or veneers from round logs without requiring preliminary preparation of the logs except as to their length, and causing the logs to be free from restrictive pressure for automatic gravitation at predetermined intervals, or at such times relatively to the operation of the cutters as to be in proper position at all times for engagement by the said cutters without requiring manual adjustment or setting of the logs.

A further object of the invention is to provide a wood slicing or veneer cutting machine having a relatively increased production of cut slices or veneers by disposing opposed logs in the machine for alternate engagement by the cutting means, and whereby the cutting operation may be pursued in connection with two logs.

A further object of the invention is to provide automatically operating means for holding the log in fixed position during the movement of the cutting means into engagement with and through the log, to ensure the formation of a regularly cut slice or veneer.

A still further object of the invention is to generally improve the structural organization of machines of this class, and particularly to simplify and reduce the number of cooperating parts thereof without detracting from the requisite strength and durability of cutting or slicing machines.

With these and other objects and advantages in view, the invention consists in the preferred construction and arrangement of parts which will be more fully hereinafter described and claimed.

In the drawings:

Fig. 1 is a side elevation of the improved slicing or veneer cutting machine, showing the feed means or runways in transverse vertical section;

Fig. 2 is a top plan view of the improved machine;

Fig. 3 is an end elevation of the same, showing the feed means or runways at opposite sides broken away;

Fig. 4 is an enlarged transverse vertical section through the feed table or bed and oppositely disposed sides of the frame together with the cutting means, and showing the manner of slicing or cutting the veneers and disposing them upon a transferring means below;

Fig. 5 is an enlarged top plan view of a portion of the knife carrier and knives;

Fig. 6 is a transverse vertical section on the line 6—6, Fig. 5;

Fig. 7 is a detail plan view of one of the dog organizations for engaging one end of the log, a part of the log being shown in section with the dog teeth in engagement therewith; and

Fig. 8 is a plan view of the dog organization shown by Fig. 7 looking toward a different side of the same.

The numeral 5 designates a base plate having pillars or posts 6 rising therefrom a suitable distance for the support of a bed 7 formed with a central opening 8. On this frame angular side rails or members 9 are held at an elevation by end supports 10, the angular side rails having vertical members 11 which serve as brace walls for opposing logs deposited in the machine in a manner and for a purpose which will be more fully hereinafter explained. Fully open spaces 12 are formed between the opposite ends of the angular side rails 9, and by elevating the latter, side openings 13 are also provided for movement and clearance of the mechanism in its lateral operation. Associated with the opposite angular side rails 9 are runways or feed means 14 disposed at downward and inward angles of inclination and on which the logs to be operated upon are placed and caused to gravitate or move towards the upper edges of the vertical members 11 of the said side rails. These runways or guide means 14 may be provided with any of the well known and approved mechanisms for controlling the movement of the logs thereover for feed to opposite sides of the machine.

At suitable distances inwardly from the ends of the angular side rails 9, cross connecting members 15 are located and

secured to the said side rails and have inner depending vertical flanges 16 terminating coincidently with the lower sides of the said side rails, so as to preserve the longitudinal 5 openings extending through the ends of the machine between said side rails and the supports 10. Rising from the opposite ends of the connecting members are uprights 17 connected by cross bars 18 at their intermediate portions.

A longitudinal drive shaft 19 is held on the base 5 at a suitable elevation in bearings 20, this shaft extending outwardly beyond the ends of the said base and having on one 15 end a drive pulley or band wheel 21 adapted to receive power from any suitable source. This shaft 19 is arranged at one side of the longitudinal center of the machine and has thereon worms 22 held in continual mesh 20 with worm wheels 23 fixed on upright shafts 24 having suitable bearings 25 in the base 5, as at 26, and also in the opposite ends of the bed 7, these shafts 24 projecting through the bed 7 and having horizontally disposed 25 eccentric disks 27 centrally fixed thereto and provided with eccentric wrist pins 28. By this means the eccentric disks 27 are uniformly rotated at the same rate of speed, the worms 22 and worm wheels 23 being all 30 similar in dimensions and pitch. On the end of the driving shaft 19 opposite that having the band pulley 21 attached thereto is a transmitting pulley 29, by means of which upper mechanism may be actuated. 35 It will be seen, therefore, that all of the mechanisms of the machine are operated from the shaft 19 in a very simple manner, and the upper actuating mechanism, which pertains more particularly to the devices for 40 engaging the logs deposited in the machine to undergo the slicing or cutting operation, will be hereinafter clearly explained.

Fixed on the upper side of the bed 7 and at suitable distances apart are transverse 45 rails 30 having grooves 31 in their upper sides. These rails, as shown by Fig. 2, extend out equal distances beyond opposite sides of the angular side rails 9, as shown by Fig. 3, and on these rails a laterally reciprocating log support 32 is mounted and provided with lower flanges 33 freely movable in the grooves 31. The log support or frame is slatted, as at 34, the slats extending inwardly to central longitudinal guide 50 rails 35 shown particularly by Figs. 4 and 6, the said rails 35 being separated by an opening 36 between their inner sides and also having slots 37 extending the full length thereof. Mounted to longitudinally 55 travel in the opening 36 between the inner edges of the guide rails 35 are vertical pins 38 having grooved rollers 39 thereon to receive the inner side edges of the rails 35, as clearly illustrated by Fig. 6, the top portions 60 of the said rails being stepped, as at 65

40, to permit the upper flanged portion of the rollers 39 to fit thereinto and also provide for a comparatively close disposition of the upper or top edges of the rails 35 relatively to the lower sides of a carrier 70 41 fixed on the pins 38 and having cutting blades 42 secured to opposite sides thereof and projecting beyond the side edges of the carrier. The upper ends of the pins 38 are reduced, as at 43, and secured in the 75 center of the carrier 41, and the lower ends of these pins are suitably threaded to receive nuts 44 to secure all of the parts in operative sliding positions and to permit the rollers 39 to have sufficient play to reduce friction but at the same time render them effective in the desired operation of the several parts. The cutters or knives 42 are mounted in angular seats or recesses 45 formed in the upper opposite side portions 80 of the carrier 41 and removably retained in operative position by fastenings 46, whereby the said blades or knives may be detached and sharpened when found necessary and then reapplied or replaced in the 85 event of breakage by other similar devices. The cutting bevels of the blades or knives 42 extend upwardly from the lower sides of the same and intersect the top sides, as at 47, and the upper or top sides of the 90 said plates are flush with the upper side of the carrier 40, the fastening devices 46 being countersunk. By this means a horizontally smooth top surface is provided in the association of the blades or knives 42 and the carrier 41 for effective operation in cutting or slicing logs. The opposite ends of the carrier 41, as clearly shown by Fig. 5, are reduced and have suitable bearing devices 48 secured thereto, said bearing devices being similar to cross head connections for receiving the wrist pins 28 of the disks 27, and whereby the motion of the 95 said disks is imparted to the carrier and from the latter to the laterally reciprocating 100 log support or frame 32. At the opposite sides of the reciprocating log support or frame 32 and preferably at the corners of the latter are horizontally disposed wiping rollers 49 for operation of log end engaging dogs 105 50 shown in detail by Figs. 7 and 8 and disposed in pairs at opposite extremities of the machine, as clearly shown by Fig. 2. These dogs are intermediately stepped, as at 51, as shown by Figs. 3 and 8, and are 110 also disposed on the horizontal members 52 of the side rails 9 and fulcrumed as at 53, the intermediate stepped portions 51 of these dogs depressing the outer extremities thereof to provide contact arms 54 having their inner edges in position for engagement by the wiping rollers 49. The opposite pairs of these dogs are connected by 115 springs 55 attached at suitable distances 120 outwardly beyond the fulcrums 53 thereof, 125 130

so as to normally draw the contact arms 54 inwardly in angular relation and throw out the inner arms 56, the latter arms carrying a plurality of inwardly projecting pins or 5 spikes 57 which are freely movable through slots 58 formed in the depending flanges 16 of the end connecting members 15 for the side rails 9. As the laterally reciprocating log support or frame 32 moves over 10 and in engagement with the rails 30 therefor, the wiping rollers 49 are alternately brought into engagement with the opposite pairs of normally inwardly drawn contact arms 54 and the inner arms 56 of these dogs 15 are gradually moved inwardly and the pins or spikes are forced into the opposite ends of each log in line therewith just at the time that the cutting blade on that side comes into engagement with the lower portion 20 of the log to perform its cutting operation, and by this means the log is prevented from turning. The moment that the reciprocating log support or frame 32 recedes in alternation so as to release the arms 54 from outward pressure through engagement therewith of the wiping rollers 49, the springs 55, which are distended during this engaging operation, come into play to draw the released arms 54 inwardly into normally angular positions and throw the inner arms 56 and the pins or spikes 57 outwardly, or disengage the said pins or spikes from the log ends, so that the logs will always be ready for automatic settling 30 35 adjusting movements.

The cross bars 18 fixed to the uprights 17 steady or reinforce the latter, and said uprights are continued above these cross bars in the form of extensions 17^a. The uprights 17 and their extensions are further reinforced by side rails or longitudinal bars 18^a, which may be continuous with the cross bars 18 or otherwise associated with the latter, to give this superstructure sufficient 40 strength and rigidity to serve both as a supporting means and for the operation of devices which will be presently explained. In bearings 59 mounted on the central portions of the cross bars 18 is a longitudinal power transmitting shaft 60 projecting at opposite extremities outwardly beyond the said bearings and having fixed thereon friction pulleys or disks 61 and 62. Adjacent to the friction pulley or disk 61 the shaft 60 is projected a greater distance beyond the nearest bearing 59 therefor and has a band pulley 63 fixed thereon over which runs a belt 64 which also engages the pulley 29 on the one end of the lower drive shaft 19 and whereby power is transmitted from the latter shaft to the shaft 60. During the operation of the shaft 19 the shaft 60 is continuously rotated ready to perform its function when adjusted to bring either of the friction pulleys or disks 61 and 62 into engagement with cooperating parts. The adjustment of the shaft 60 is very slight and is lateral, such adjustment being accomplished by having the base plate 65 of each bearing 59 slotted as at 66, to permit shifting of the bearing and the adjacent extremity of the shaft relatively to the connecting bar 18, the latter having sufficient width, as shown by Fig. 2, to permit this operation to be practically effected. The shaft 60 is disposed in central relation and is normally parallel with opposite pinion shafts 67 and 68, each of these shafts carrying two pinions 69 located as shown by Fig. 2. The shafts 67 and 68 are mounted 70 in fixed bearings 70 secured on the cross bars 18, and on the one end of the shaft 67 is a friction pulley or disk 71, and on the one end of the shaft 68 is a similar friction pulley or disk 72, the pulleys or disks 71 and 72 being in reverse positions to engage the friction pulleys or disks 62 and 61. The friction pulleys or disks 71 and 72 are of greater diameter than the friction pulleys or disks 62 and 61 with which they respectively cooperate, so as to give the shafts 67 and 68 proper timed operation when the opposite extremities of the shaft 60 are shifted to bring these frictional components 80 85 into engagement. On the shaft 67 adjacent to the friction pulley or disk 71 is a brake disk 73 engaged by a brake band 74 attached to the upper end of a lever 75 fulcrumed on the adjacent cross bar 18, as at 76, the lever 75 extending downwardly such length as to be within convenient reaching distance of an operator. An arm 77 extends inwardly from the lever 75 below the fulcrum 76 and is movably attached to the lower shank or stem 78 of a shifting fork 79 fulcrumed on the outer edge of the adjacent cross bar 18, as at 80, and whereby the lever 75 may be operated to simultaneously shift the adjacent extremity of the shaft 60 and release the brake band 74 from the brake disk 73, and whereby, also, the friction pulley or disk 62 is brought into contact with the friction pulley or disk 71 and the shaft 67 90 95 set in operation. The same mechanism is applied to the shaft 68, the latter having a brake disk 81 fixed thereon engaged by a brake band 82 connected to the upper end of a lever 83 similarly fulcrumed on the opposite cross bar 18 and also having an arm 84 connected to the shank 85 of a shifting yoke 86, and whereby the opposite extremity of the shaft 60 may be reversely shifted to bring the friction pulley or disk 61 into engagement with the friction pulley or disk 72 and operate the shaft 68. The levers 75 and 83 are controllable or may be moved to such a degree and in proper direction to effect a brake either of the shafts 67 and 68 or to release the said shafts for free rotation. The pinions 69 on the respective 100 105 110 115 120 125 130

pinion shafts 67 and 68 are continually engaged by racks 87 rigidly secured to upper longitudinal slides 88 mounted on the extensions 17^a of the uprights 17 and also to lower slides 89 movable on the said uprights 17 below the cross bars 18. Between the racks 87 on each side of the central shaft 60 and outside of the shafts 67 and 68, vertically movable dogs are secured to the slides or slide bars 88 and 89 and comprise stems 90 having lower laterally projecting heads 91 formed with bottom serrated edges 92. The stems 90 are firmly secured to the upper and lower slides or slide bars 88 and 89 but are freely movable through openings 93 formed in the side rails or bars 18^a extending from the cross bars 18. By this means these dogs are steadied in their movement and prevented from having the least lateral play. The lower ends or heads 91 of the dogs are so positioned that they will move downwardly and clear the inner surfaces of the vertical members 11 of the angular side rails 7, and the functions of these vertically moving dogs is to bear on and hold the opposing logs in the machine and operated upon by the cutting mechanism hereinbefore described against vertical movement. It will therefore be seen that the logs operated upon by the cutting mechanism are prevented from rotating through the action of the dogs 50 and held against vertical movement by the dogs disposed thereover and just described. The friction mechanism together with the brake devices interposed between and cooperating with the shafts 60, 67 and 68 are for the purpose of raising the dogs, including the stems 90 and heads 91, positively to such elevations that successive logs may be fed into the cutting space between the vertical members 11 of the angular side rails 9 and onto the log support 32 and then be controlled as to gradual rolling movement without a sudden drop through the operations of the levers 75 and 83 and the devices in connection therewith for shifting the opposite extremities of the shaft 60 and also for controlling the brake means on the shafts 67 and 68. After the dog heads 91 are in engagement with the logs, which is the normal position of these dog heads, they will be free to gravitate automatically with the logs as the latter are reduced by successively cutting slices or veneers therefrom, and consequently, during the cutting operation these vertically moving dogs do not require any manual attention, in view of the fact that the shafts 67 and 68 at such time are free to run loose, or are not restricted by the braking means on the said shafts.

A conveying means is mounted under the bed 7 to carry away the cut slices or veneers, said conveying mechanism consisting of an endless belt 94 moving transversely under

the bed 7 and trained over opposite rollers 95 mounted on shafts 96 rotatable in bearings 97 mounted on bearing pedestals 98. One of the shafts 96 is provided with a band pulley 99, as shown by Fig. 1, and on the shaft 19 is a similar band pulley 100, the pulleys 99 and 100 having a belt 101 trained thereover for transmitting power from the shaft 19 to the one shaft 96 for causing the belt 94 to be driven, the upper member of the said belt being comparatively close to the underside of the bed 7 so as to receive the cut slices or veneers. From the belt 94 the slices or veneers of wood are delivered to an incline 102, or may be deposited in any other manner for transportation away from the machine.

The operation of the machine is very simple. The opposite runways or log guides, which may be of any length, have a number of logs disposed and held thereon and individually fed into opposite sides of the machine between the vertical members 11 of the angular side rails 9 and rest on the reciprocating log support or frame 32. After two logs have been disposed in the machine as shown by Fig. 3, the dogs comprising the shanks 90 and heads 92 are permitted to gravitate until the serrations 92 at the lower edges of the heads 91 engage the logs and hold the latter, the weight of these dogs and the frame device carrying the same being sufficient to hold down the logs against any tendency to rising movements. The shaft 19 is then set in motion and through the gear connections hereinbefore explained the disks 27 are simultaneously rotated and the carrier 41 is reciprocated longitudinally and moves, for example, first towards the vertical member 11 of one angular side rail 9 and simultaneously shifts the log support or frame 32 therewith, thereby causing the one log towards which the movement of the carrier with its knives or blades 42 has taken place to be firmly jammed against the adjacent vertical member 11 of the nearest angular side rail 9, and at the same time the wiping rollers 49 on that side of the machine coming into engagement with the contact arms 54 will force the said arms apart against the resistance of the spring 55 connecting the same and move the inner pin or spike carrying arms 56 inwardly to cause the pins or spikes 57 to become imbedded in the opposite ends of the log. The carrier 41 with the blades or knives 42 and the log support or frame 32 continues to move gradually over during the cutting operation, as shown by Fig. 4, and until the one cutter or blade has completed the severance of the slice or veneer, the carrier with the blades being given a draw cut motion during the movement of the carrier and its blades through the log, owing to the eccentric attachment of the

ends of the carrier to the disks 27. As each slice or veneer is cut from the one log it is fed downwardly through the nearest slot 37 through the central opening 8 of 5 the bed 7 and falls onto the belt or conveyer 94 and is taken by the latter outwardly in a transverse direction to one side of the machine and deposited either on the incline 102 or in some other manner, as may be 10 desired. After the severance of the slice or veneer from one log is completed, the eccentrics or disks 27 will be in such position as to cause a reverse or return movement of the carrier 41 and its blades or 15 knives 42 towards the center of the cutting space between the vertical members 11 of the angular side rails 9, and at the same time the log support or frame 32 will have a similar movement imparted thereto 20 through the action of the pins and rollers 39 working in the longitudinal opening or slot 36 in the log support or frame 32. The moment that the log support or frame 32 starts and continues to recede from its 25 closest position relatively to one of the angular side rails and after a slice or veneer has been severed, the contacting pressure on the arms 54 is gradually reduced and these arms are drawn together by the retraction 30 of the springs 55 connected thereto and the inner pin or spike carrying arms 56 of the dogs and the pins or spikes 57 are withdrawn from the ends of the log that has just been cut, thereby allowing the latter 35 log to gravitate or settle in position for a further cutting operation, and at the same time the upper or top pressure dogs having the heads 91 with the lower serrated edges 92 follow the log and maintain the same 40 engaging relation therewith. This operation is effected alternately with respect to the two logs, and after the logs have been fully cut or sliced, they will be replaced by other similar logs and the same operation 45 ensues. It will be understood that the cut slices or veneers of wood from the opposite logs will be delivered through the opposing slots 37 and the latter are preferably so arranged as to encourage and permit 50 the cut slices to pass easily therethrough, the stepped portions of the rails 35 at the top of the central slot or longitudinal opening 36 preventing the cut slices or veneers from jamming under the carrier and failing 55 to pass through the discharge slots 37 as desired and intended. The operation of the machine will be very expeditious, particularly in view of the double cutting action, or whereby two logs are alternately operated 60 upon during the travel of the carrier 41 and the knives or blades 42 from one side of the cutting space to the other. By this means there is no lost motion, or in other words, all motions of the carrier and its 65 knives or blades are brought into play or

service in performing a cutting operation. The cutting operation is greatly assisted and rendered more practical by the automatic operation of the end and top holding dogs for the logs, and also by the automatic 70 operation which ensues without requiring manual manipulation and delays incident thereto, especially in resetting or disposing the logs in position after each cut is made. The reverse movements of the reciprocating 75 log support or frame in consonance with the actuation and through the drive of the carrier 41 and its knives or blades 42 will be exceptionally advantageous in first moving each log outwardly towards its side rail member to assist in holding the log tightly 80 against said side rail member and then sufficiently releasing each log or withdrawing all restrictive pressure therefrom after the cutting to permit free gravitation 85 of the cut log. When it is desired to dispose a new log in the cutting space between the angular side rails 9, either one of the levers 75 or 83 is operated to shift the ends of the shaft 60 and set up a frictional operation 90 from the latter relatively to either one of the shafts 67 and 68 to forcefully raise either of the sets of dogs comprising the shanks 90 and head 91, so as to clear the space below these dogs for placement of a 95 log in the cutting space of the machine. It will be seen that two of the top pressure dogs are used on each side and engage each 100 log. This number may be increased as found desirable in accordance with the proportions of the machine. It will be understood that the machine will be equipped with mechanism usually employed for quickly starting and stopping the drive shaft 19, or in shifting the belt that may 105 be positioned to engage the pulley 21.

To give proper direction of rotation to the shaft 67 and elevation of the racks 87 operated by the pinions 69 thereon, an idler friction pulley or disk 103 is mounted between the friction pulley or disk 62 on the shaft 60 and the friction pulley or disk 71 on said shaft 67. The idler friction pulley or disk 103 is carried by a suitable bearing bracket 104 secured on the end of the adjacent frame. 110

It will be understood that changes in the proportions and dimensions of the several mechanisms and adoption of well known mechanical accessories in machines of this type may be made as found necessary without departing from the spirit of the invention. 115

What is claimed as new is:

1. A wood cutting machine of the class specified, having walls defining a cutting space for receiving and holding a number of logs, and longitudinally reciprocating cutting mechanism having cutting blades at opposite sides transversely movable across said 120

- 6 space and operating between and alternately cutting slices from the lower portions of the logs by draw-cut actuation.
2. A wood cutting machine of the class 5 specified, having walls defining a cutting space for receiving and holding a number of logs, transversely reciprocating means for supporting the logs, and longitudinally reciprocating cutting mechanism having cutting blades at opposite sides transversely movable across said space and alternately operating upon and cutting slices from the lower portions of the logs by draw-cut actuation.
- 15 3. A wood cutting machine of the class 10 specified, having walls defining a cutting space for receiving and holding a number of logs, longitudinally reciprocating cutting mechanism having cutting blades at opposite sides transversely movable across said space and operating between and alternately cutting slices from the lower portions of the logs by draw-cut actuation, and dog devices 15 for engaging the ends of the logs during the time they are cut and also bearing on the top portions of the logs, the dog devices being operable to permit the logs to automatically settle immediately after each log has been cut.
- 20 4. A wood cutting machine of the class 20 specified having walls defining a receiving space for longitudinal disposition of logs therein adjacent to the said walls, and longitudinally and transversely reciprocating mechanism located at the lower portions of the said walls and the logs in the space defined by the latter, the said mechanism having cutting devices at opposite sides to alternately cut the lower portions of the logs by 25 draw-cut actuation.
- 45 5. A wood cutting machine of the class 30 specified, having walls defining a cutting space for receiving and holding a number of logs, dog devices engaging the logs for holding the latter against movement at intervals, and longitudinally reciprocating cutting mechanism operating between and alternately cutting slices from the lower portions of the logs by draw-cut actuation, the logs being 35 released between each cutting operation in relation thereto for automatic settling in a proper position for a further similar cutting operation.
- 55 6. A wood cutting machine of the class 40 specified having walls enclosing a space for longitudinal disposition and spaced relation of the logs therein, and longitudinally and transversely reciprocating mechanism beneath the logs and including opposed side cutting blades movable between the lower 45 portions of the logs and alternately to and through the said portions of said log by draw-cut actuation.
- 65 7. A wood cutting machine of the class 50 specified, having walls enclosing a cutting 55 space for receiving and holding a number of logs, a transversely reciprocating frame for supporting the logs and forming the bottom for the space, and longitudinally reciprocating cutting mechanism associated with and operating the said frame and alternately and regularly shiftable towards and through the lower portions of the opposite logs and having draw-cut actuation.
8. A wood cutting machine of the class 60 60 specified, having walls enclosing a cutting space for receiving and holding a number of logs and located between side rails against which the outer portions of the logs have bearings, transversely reciprocating means for supporting the logs and forming a movable bottom for the cutting space, and longitudinally reciprocating cutting mechanism alternately operating upon the lower portions of the logs and having draw-cut actuation in relation to the logs.
9. A wood cutting machine of the class 65 specified, having walls enclosing a cutting space for receiving and holding a number of logs, transversely reciprocating bottom means for said cutting space to serve as a support for the logs, longitudinally reciprocating cutting mechanism associated with and actuating the said bottom means and alternately operating upon the lower portions of the logs by draw-cut actuation, dog devices for engaging the ends of the logs at intervals and operated by the reverse movements of the said bottom means, and gravitating dogs separably engaging the upper 70 portions of the logs.
10. A wood cutting machine of the class 75 specified, having walls enclosing a cutting space for receiving and holding a number of logs, a transversely reciprocating log supporting frame forming a movable bottom for the said cutting space, and longitudinally reciprocating cutting mechanism having devices movably engaging the center of the frame to operate the latter, the cutting mechanism alternately operating upon the lower portions of the opposite logs and having draw-cut actuation in relation to the latter.
11. A wood cutting machine of the class 80 80 specified, having walls enclosing a cutting space for receiving and holding a number of logs, a log supporting frame mounted to have a transverse reciprocation and provided on opposite sides of the center with discharge slots for the slices or veneers cut from the log, cutting mechanism having a longitudinal reciprocation between and to and through the lower portions of the logs and also having draw-cut actuation with relation to the logs, and conveying means below the frame for receiving the cut slices or veneers and depositing the latter at one side of the machine.
12. A wood cutting machine of the class 85 90 95 100 105 110 115 120 125 130

specified, having walls enclosing a cutting space for receiving and holding a number of logs, a transversely reciprocating frame for supporting the logs, longitudinally reciprocating mechanism associated with and operating the said frame and also movable alternately to and through the lower portions of the opposing logs and having draw-cut actuation, dogs for engaging the ends of the logs at intervals and actuated by the movement of the frame, and other dogs engaging the top portions of the logs and having a gravitating movement to follow the logs downwardly as the latter are cut, the latter dogs being provided with mechanism manually controllable to raise the dogs to clear the cutting space for the introduction of uncut logs. 15

In testimony whereof I have hereunto set my hand in presence of two subscribing witnesses. 20
